UNITED STATES PATENT OFFICE.

CHARLES L. MELHINCH, OF CARBONDALE, PENNSYLVANIA.

AUTOMATIC SWITCH.

Application filed December 29, 1923. Serial No. 683,345.

The chief object of the invention is to so modify the alarm mechanism of an alarm clock that said mechanism is adapted, when released at a predetermined time by the time mechanism in the usual manner, to close an electric circuit, such as the lighting circuit of an automobile, so that the lamps may be automatically lighted at the time at which the alarm mechanism is set to go off; and to effect the winding of the spring of the alarm mechanism by the operation of breaking the circuit and extinguishing the lights, so that the continued operativeness of the spring is assured without other attention by the operator than the breaking of the lighting circuit.

I attain this and other related objects by the improvements hereinafter described and claimed.

20 Of the accompanying drawings forming a part of this specification,—

Figure 1 is a side view of an automatic switch embodying the invention.

Figure 2 is a section on line 2—2 of Figures 1 and 3.

Figure 3 is a section on line 3—3 of Figure 2.

Figure 4 is a section on line 4—4 of Figure 3.

30 Figure 5 is a section on line 5—5 of Figure 3.

Figure 6 is a section on line 6—6 of Figure 5.

The same reference characters indicate the 35 same parts in all the figures.

The drawings show a clock which is enclosed in a case 10 and includes a time mechanism and well known elements of an alarm mechanism, the usual gong or audible signal being omitted. The case is oblong, as shown by Figures 1 and 3, and its dial side has at one end portion an opening 10^a exposing the clock dial. The dial side has an extended portion 10^b beside the opening, through which project the winding post and the handle of the stop hereinafter described. The time mechanism in this instance, comprises a driving spring 12, connected as usual, with a gear 14, meshing with a pinion 15, on the center arbor 16. This arbor carries the minute hand 17 and the usual tubular shaft or sleeve 18, carrying the hour hand 19. The other illustrated elements of the time mechanism are so well known that no further description is deemed necessary.

The alarm mechanism, as here shown, comprises a driving spring 20, adapted, as usual, to rotate an arbor 22 in the direction indicated by the arrow *x* in Figure 3, when the alarm mechanism is released at a predetermined time by a trip or let-off device operated in the usual way, by the time mechanism, the rotation of the arbor being controlled by a suitable escapement, such as that shown by Figure 3, including an escape 60 wheel 23, geared to the arbor 22, and an anchor 24, having the usual pallets and adapted to be oscillated by the rotation of the escape wheel.

In an ordinary alarm clock the anchor 24 70 is provided with a hammer, which strikes a gong when the anchor is oscillated, and with a finger 25, which is adapted to cooperate with the above-indicated let-off device, to release the alarm mechanism at a predetermined time, which is determined by the 75 rotative adjustment of the usual setting shaft 26, having at its outer end portion a trip cam 27 and a pointer 28. It is unnecessary to further describe the alarm-releasing means, 80 further than to say that the setting shaft 26 is provided with a bevel-gear 29, the function of which will be described.

In carrying out my invention I utilize the arbor 22, to move a circuit-closing switch 85 when the alarm mechanism is released by the let-off device, the hammer and gong being omitted.

Said switch includes a movable member or switch arm 30, fixed to the arbor 22, and a 90 pair of spring contacts or circuit terminals 31, spaced apart to receive the arm between them, as shown by Figure 4. The terminals 31 are insulated from each other by insulating washers 32 and 33 (Figure 4), and are 95 included in a lighting circuit which includes headlights 34, a tail light 35, a source of electricity 36, and suitable circuit wires, all as shown diagrammatically by Figure 3.

The arrangement is such that when the 100 alarm mechanism is locked and inoperative, the switch arm 30 is separated from the terminals 31, as shown by full lines, the lighting circuit being broken, and when the alarm mechanism is let off, the switch arm 105 is moved to the dotted line position, and engages the terminals to close the lighting circuit.

The switch arm is provided with a gear segment 38, constituting an element of means 110

for restoring the switch arm to its circuit-breaking position, and at the same time, winding the spring 20. Said mechanism also includes a winding post 39, journaled in and 5 projecting through the extended portion 10^b of the dial side of the case 10, and provided at its outer end with a knob or handle 40, a gear 41, fixed to the winding post within the case, and an intermediate gear 42 meshing 10 with the gear 41 and gear segment 38.

It is usually desirable that the lighting circuit be automatically closed only at the hour prescribed in the latter part of the day for lighting motor vehicle lamps. To prevent 15 the alarm mechanism from closing the circuit at the corresponding hour in the morning, I provide a stop 44, which is slideable on the back of the extended portion 10^b, and is provided with a slot 45, receiving a stud 46, fixed to the case 44^a, and with a stud 47, movable in a slot 48 in the said extended portion, and provided with a handle 44^a (Figure 1). The stop is movable 20 by said handle into the path of the switch 25 arm 30, as shown by full lines, and out of said path, as shown by dotted lines, the handle 44^a projecting from the dial side of the case.

It will now be seen that when the alarm 30 mechanism is released, the stop being retracted, the lighting circuit is closed and the lamps therein remain lighted until the circuit is broken by the withdrawal of the switch arm 30 from the contacts 31.

It will also be seen that the operation of 35 withdrawing the switch arm, which is manually performed by turning the handle 40, causes the winding of the alarm spring 20, so that no care is required to keep said spring wound. It should be here stated that the alarm mechanism includes, as usual, a 40 ratchet 50, and a pawl 51 (Figure 3), which cooperate to limit the manual rotation of the winding post to one direction only, this being the direction required to cause the 45 winding of the spring 20, and the withdrawal of the switch arm from the circuit terminals.

It will now be seen that extension 10^b of 50 the dial side of the case supports the winding post and the stop at one side of the dial, and permits the location of the handles of the winding post and stop in position to enable the driver to wind the spring, break 55 the circuit and adjust the stop, without removing the clock from the case.

My invention includes improved mechanism for winding the time spring 12, setting the hands, and rotatively adjusting the alarm 60 setting shaft 26, said mechanism being operable by a single operating shaft 53, which is rotatable and movable endwise, and projects through the casing 10, the shaft being provided with a knob or handle 54, where- 65 by it may be rotated and moved endwise,

the arrangement being such that by suitably manipulating the handle 54, the above-mentioned operation may be separately performed.

The operating shaft 53 is journaled and 70 movable endwise in a bearing 55, and is provided with a gear 56, which is fixed to the shaft. Meshing with the gear 56 is an intermediate gear 57, fixed to a short shaft 58, which is journaled in bearings in supporting plates 59 and 60, and is provided with collars 61 engaging said plates, and confining the same, so that they are movable by the operating shaft 53 when the latter is moved endwise.

In the plate 59 is journaled a short shaft 62, which is supported by and movable endwise in a bearing 63. To the shaft 62 is fixed a gear 64, meshing with the intermediate gear 57.

Journaled in one end of the plate 60 is a shaft 65, alined with the operating shaft 53, and provided with a ratchet 66, engaging a pawl 67, which is pivoted to the gear 56. The shaft 65 is elongated and provided with a bevel gear 68, adapted to mesh separably with a bevel gear 69 on the center shaft 16. The shaft 65 is provided also with a bevel gear 70, adapted to mesh separably 95 with the bevel gear 29 on the alarm setting shaft 26.

Journaled in the opposite end of the plate 60 is a shaft 71, alined with the short shaft 62, and provided with a ratchet 72, engaging a pawl 73, which is pivoted to the gear 64. The shaft 71 is elongated and provided with a bevel gear 74, meshing continuously with a bevel gear 75, fixed to the shaft 76, which is rotated by the main spring 12. The shaft 71 may be made in two sections, having a slip joint at 77, so that the inner shaft portion having the pawl 73, may be moved endwise, without movement of the outer portion having the gear 74, provision being thus made for permitting endwise movement of the shafts 53, 62 and 65, and the inner portion of the shaft 71, the outer portion of the last-mentioned shaft, and the gear 74 carried thereby, having no endwise movement, and the gear 74 being constantly in engagement with the gear 75.

The supporting plate 59 is confined against the gears 56 and 64 by collars 80, fixed to the shafts 53 and 62. The supporting plate 60 is similarly confined against the ratchets 66 and 72 by collars 81, fixed to the shafts 65, and to the longitudinally movable inner portion of the shaft 71. Provision is thus made for moving the said shafts endwise in unison, as indicated by full and dotted lines in Figure 2. When the shafts are in one position, the gear 68 meshes with the gear 69 of the center shaft, and the gear 70 is out of mesh with the gear 29 of the alarm-setting shaft, as shown by full lines.

The ratchets 66 and 72 are oppositely arranged, as shown by Figure 5, the arrangement being such that when the gear 68 is engaged with the center shaft gear 69, the only result of the rotation of the handle 54 is the setting of the clock hands, there being no rotation of the shaft 71, because the pawl 73 slips idly on the ratchet 72.

When the gear 70 is engaged with the gear 29 of the alarm-setting shaft, the only result of the rotation of the handle 54 is the rotative adjustment of said setting shaft. The handle 54 is rotated in one and the same direction both in setting the hands and adjusting the alarm-setting shaft.

The winding of the main spring 12 is caused by an opposite rotation of the handle 54, this rotation causing the pawl 73 to operatively engage the ratchet 72 and rotate the shaft 71 and the gear 74 engaged with the main spring shaft, the pawl 67 slipping idly on the ratchet 66, so that the shaft 65 and its gears are not rotated.

It will now be seen that the operator is enabled to separately set the clock hands and the alarm mechanism and wind the time-mechanism spring by the manipulation of a single knob or handle, instead of having to separately manipulate a plurality of knobs or handles as heretofore.

I am not limited to the torque-transmitting connections between the single operating shaft 53, and the shafts 16, 26 and 76, shown by the drawings, and may employ any other suitable connections having provisions for turning either of the shafts 16 and 26 selectively, without turning the other and the shaft 76, when the operating shaft 53 is turned in a given direction, and for turning the shaft 76 independently, without turning the shafts 16 and 26 when the operating shaft is turned in the opposite direction.

The case 10 is preferably attachable in

the inclined position shown by Figure 2, to the dash 85 of an automobile, the case being provided with flanges 86, which are bolted to the dash at opposite edges of an opening in the latter, so that the lower portion of the case, and the operating knob or handle 54 projecting therefrom, are at the inner or rear side of the dash facing the driver, the clock dial being inclined, so that it may be conveniently seen by the driver.

I claim:

An alarm clock, comprising alarm mechanism including a driving spring, an arbor rotatable thereby; means for timing the release of the alarm mechanism including a rotatively adjustable setting shaft; and time mechanism which includes a driving spring, a spring-winding shaft and a center shaft constituting an element of hands-setting means; a switch arm fixed to and movable by said arbor; circuit terminals adapted to cooperate with said arm in closing an electric circuit, when the alarm mechanism is released; and operating mechanism for manually and separately operating said shafts to time the release of the alarm mechanism, set the hands, and wind the time-mechanism spring, said operating mechanism including a single operating shaft which is manually rotatable and movable endwise, torque-transmitting connections between said operating shaft and the said alarm setting and center shafts, having provisions for turning said shafts selectively when the operating shaft is turned in a given direction, and torque-transmitting connections between the operating shaft and the spring-winding shaft, having provisions for turning the latter when the operating shaft is turned in the opposite direction.

In testimony whereof I have affixed my signature.

CHARLES L. MELHINCH.
